UNITED STATES PATENT OFFICE.

ARCHIE E. PARNALL, OF CHICAGO, ILLINOIS, ASSIGNOR TO FRANK W. WILLIAMS, OF CHICAGO, ILLINOIS.

TALKING-MACHINE MECHANISM.

1,265,493.

Specification of Letters Patent. Patented May 7, 1918.

Application filed September 18, 1916. Serial No. 120,819.

To all whom it may concern:

Be it known that I, ARCHIE E. PARNALL, a citizen of the United States, residing at Chicago, in the county of Cook and State 5 of Illinois, have invented new and useful Improvements in Talking-Machine Mechanism, of which the following is a full, clear, concise, and exact description, reference being had to the accompanying drawings, forming a part of this specification.

My invention relates to talking machine mechanism.

One of the objects of my invention is to provide improved means whereby the tone 15 arm may be connected with machines having different types of amplifiers.

In the drawings, in which my invention is shown—

Figure 1 is a vertical section of a talking 20 machine in which the amplifier is inclosed in a casing below the record support; and

Fig. 2 is a vertical section of a talking machine in which the amplifier is mounted above the record support.

Referring to the drawings in detail and first to Fig. 1, the talking machine here shown comprises a casing 10, driving transmission mechanism 11 mounted in the casing, a record support 12 driven from the 25 mechanism 11, a tone arm 13, a sound box 14 supported by the tone arm, and an amplifier 15 with which the tone arm 13 communicates inside the casing 10 and below the record support.

Referring to Fig. 2 the talking machine here shown comprises a casing 16, having a top or cover 17 hinged thereto at 17^a, an amplifier 18 supported by the cover 17 to swing therewith, a support or partition 19 30 for the driving transmission mechanism 20, and a record support 21 driven from the mechanism 20. The tone arm 13 and sound box 14 may be the same as in Fig. 1.

In order that the tone arm may be made 45 to communicate either with an amplifier below the record support, as in Fig. 1, or with an amplifier above the record support, as in Fig. 2, the tone arm has a straight tubular portion 22 for communication with the sound box, and a tubular elbow portion 23 for communication with the amplifier 50 rotatably and telescopically connected with the straight portion at 24. In order that the sound box may be used either with a hill and dale groove record or a laterally 55 undulating groove record, it is mounted to rotate on the tone arm about an axis lying in a vertical plane through the axis of the tone arm, from a position in which the needle is directly under the axis of the tone arm for 60 use with the hill and dale groove record, to a position at one side of this vertical plane for use with a laterally undulating groove record. For this purpose the sound box has a central axial tubular projection 25 rotatably mounted in the down-turned tubular 65 end portion 26 of the tone arm.

For holding the sound box in position on the tone arm a screw 27 may be threaded through the tubular portion 26 and extend 70 into a slot 28 in the projection 25. In order that simply pulling out or pushing in the straight portion 22 of the tone arm will effect rotation of the sound box a link 29 has a pivotal connection 30 with the sound 75 box adjacent the needle holder 30^a, and pivotal connections 31 and 22 on opposite sides of the elbow portion 23 are provided for the other end of the link 29 so that the link can be connected to the elbow portion 80 either in the position shown in Fig. 1 or in the position shown in Fig. 2.

The rotation of the sound box necessitates a tilting movement of the tone arm about a horizontal axis in addition to the swinging movement about a vertical axis. To provide for this movement about horizontal and vertical axes a tubular support and connection 33 has a central bearing 34 in which is mounted a shaft or pin 35 which carries 85 a cross shaft or pin 36 about which the tone arm tilts as an axis. The pin 35 is held in position in the bearing 34 by means of a nut 37 threaded on the end of the pin and a coil spring 38 located between the 90 nut and the bearing. The tubular support 33 is provided with a flange 39 which in the machine shown in Fig. 1 engages the support 40, and in the form of machine shown in Fig. 2 engages the support 41. The tubular support 33 may be secured to the supports 40 and 41 by means of screws 42 extending through the flange. In the machine shown in Fig. 2 a felt washer 43 may be provided to engage the entrance to the 95 amplifier 18 to act as a cushion and provide a tight connection. To remove the tone arm 13 from the machine of Fig. 1 and place it in the machine of Fig. 2 the screws 39 are removed, the link 29 is disconnected 100 and the tone arm is rotated so that the 105 connection 31 is disengaged from the connection 22. The tone arm is then removed from the machine of Fig. 1 and placed in the machine of Fig. 2, the link 29 is reconnected to the connection 31, and the tone arm is rotated so that the connection 31 is engaged with the connection 22. The tone arm is then secured to the machine of Fig. 2 by the screws 39.

at 31. The portions 22 and 23 of the tone arm are rotated relative to each other through an angle of 180 degrees. The link 29 is connected with the elbow portion of the tone arm at 32, the tubular support 33 is placed in position as shown in Fig. 2 and the screws 39 are inserted to hold the support 33 in place. The top or cover 17 is then turned down to the position shown in Fig. 2 bringing the smaller end of the amplifier down on the felt washer 43.

Having thus described my invention what I claim as new and desire to secure by Letters Patent is:—

1. A talking machine mechanism comprising a record support, an extensible tone arm, a sound box mounted to rotate about an axis lying in a vertical plane through the axis of the tone arm from a position in which the needle will properly engage a laterally undulating groove record to a position in which it will properly engage a hill and dale groove record, means whereby extending said tone arm will cause rotation of said sound box, and an amplifier connec-

tion constructed so that it can be made to communicate either with an amplifier below the record support or with an amplifier above the record support.

2. A talking machine mechanism comprising a record support, an extensible tone arm, a sound box mounted to rotate about an axis lying in a vertical plane through the axis of the tone arm from a position in which the needle will properly engage a laterally undulating groove record to a position in which it will properly engage a hill and dale groove record, said tone arm comprising two sections telescopically connected, one of said sections supporting said sound box and means whereby the extension of said tone arm will cause rotation of said sound box, said means including a link pivotally connected to said sound box and adapted to be pivotally connected to the other section in two different positions of rotative adjustment.

In witness whereof, I have hereunto subscribed my name.

ARCHIE E. PARNALL.
